BY Wm. Habell Fisher
ATTORNEY.

UNITED STATES PATENT OFFICE.

CARRIE D. JACKSON, OF MILLER TOWNSHIP, INDIANA.

SLEEVE-HOLDER.

SPECIFICATION forming part of Letters Patent No. 732,942, dated July 7, 1903.

Application filed November 3, 1902. Serial No. 129,938. (No model.)

To all whom it may concern:

Be it known that I, CARRIE D. JACKSON, a citizen of the United States, and a resident of Miller township, in the county of Dearborn and State of Indiana, have invented certain new and useful Improvements in Sleeve-Holders, of which the following is a specification.

The several features of my invention and the various advantages resulting from their use, conjointly or otherwise, will be apparent from the following description and claims.

In the accompanying drawings, making a part of this specification, and in which similar letters of reference indicate corresponding parts, Figure 1 is a side elevation of one side of the sleeve-holder. It is to be noted that the other side of the holder resembles the side shown, except that the side shown illustrates the end seams of stitching of a cloth cover. The side away from the spectator has no such seams. Fig. 2 is a view in perspective of the end portion of an ordinary sleeve and showing the sleeve-holder attached to it. Fig. 3 is a transverse section of my sleeve-holder, taken in the plane of the dotted line 3 3 of Fig. 1. Fig. 4 is a side elevation of a metal sleeve-holder without a cloth cover and illustrating features of my invention. Fig. 5 represents a vertical longitudinal central section of the sleeve-holder shown in Figs. 1, 2, and 3. The section is taken in the plane of the dotted line 5 5 of Fig. 1. Fig. 6 is a vertical cross-section of the sleeve-holder shown in Fig. 1. This section is taken in the plane of the dotted lines 6 6 of Fig. 1.

A indicates the entire sleeve-holder. (Shown in Figs. 1, 2, and 3.) The main stiff portion B of the holder consists of a thin strip of stiff material. This material is preferably of metal. Each end of this main portion B is provided with means for conveniently attaching it to the sleeve. A preferred means are pins C, after the kind known as "safety-pins." A convenient mode of connecting the pins C is by forming the material at the end of the part B into an eye B², inclosing the shank C² of that safety-pin C which is to be used at that end of the holder. Thus there will be a pin C at each end of the holder, substantially as shown in the drawings. The stiff main

part B preferably has a cover D. This is preferably made of a textile fabric of any suitable kind, and the same is when made of one piece folded over and stitched at one side—namely, where the edges meet. Where the cover D consists of two pieces, there will be a seam at each side edge of the cover. Such seams are indicated by the letter D². (See Fig. 1.) In providing this main portion B with a cover a desirable mode is as follows: A blank of metal capable of being bent under strong pressure is first provided. A cover for this is then slipped over this blank. The blank and cover are somewhat longer than the desired length of the finished stiff portion 55 of the sleeve-holder. The shank of each pin C is laid on that end portion of the stiff part where it (the pin C) is to be permanently. Then each end of the blank with the cover is bent up and around the adjacent shank of pin C. Then it will assume the shape shown in Fig. 5. Each pin is thus held in place. This portion of the sleeve-holder is now finished. There is in connection with this part an elastic connection. This connection is attached to the stiff portion and is also so made as to admit of being held by the hand while the outer coat or garment is being put over the garment to whose sleeve S the sleeve-holder is attached. The preferred mode of constructing this elastic connection and of securing it to that portion which is attached to the sleeve is as follows: An elastic strip or cord E is passed over the farther (right-hand) end, Fig. 1, and extended on both sides to a point beyond the 70 nearer (left-hand) end. The two ends of this cord E are here joined at E². This juncture may be made so as to afford a hold for the thumb and finger to grasp when the sleeve-holder is in use. One mode other than stitching the ends of the cord together or to a piece of textile fabric is to close upon these ends a metal clamp.

To prevent the cord E from slipping to one side and off from the stiff portion B, I provide loops H, one on each side of the portion B, and through each loop that part of the cord which is adjacent to that loop runs. As to the supports for the loops, these may be supported in any suitable manner. Where 75 90 95 100

the cover D is present, the loops may be attached to it. Thus in Fig. 1 each loop H is attached to the adjacent portion of the cover.

The stiff portion B is to be often employed 5 in sleeve-holders without having a cover. In such event if the stiff part is of metal it is to strike (bend) up out of the metal itself the loops H. In Fig. 4 such a construction is illustrated, the left-hand loop H being bent 10 up toward the spectator and receiving the cord E on this side of the part B and the right-hand loop being bent away from the spectator and out from the other side of the part B and receiving the cord extending on that side 15 of the part B. The loops H being duly supported, the cord E is by them prevented from slipping out of place.

Having thus described the construction of my invention, I will now proceed to describe 20 its mode of operation.

The stiff portion B, carrying the pins C or means of connection, is duly connected by such pins or such means to the inside of the sleeve of the coat or other garment over which 25 the overcoat or overgarment is to be put. The holder is usually attached in the line of the seam for obvious reasons. It is located upon the sleeve so that its lower or forward end is not at all visible and so that the lower 30 end E² of the cord E is not visible except when drawn down and held during use. Fig. 2 will illustrate the position of the sleeve-holder when attached to the sleeve S and not in use.

It is understood there will be two sleeve-holders—one for each sleeve and duly attached to the latter.

The mode of operating the sleeve-holder is as follows: The garment to the sleeves of which the sleeve-holders are respectively attached is supposed to be in place on the person of the wearer. When it is desired to put on over this garment another garment having close-fitting sleeves, then and before putting on this overgarment the wearer draws down 40 the elastic E of one sleeve-holder and holds it fast at E² in the hand of that sleeve and then draws down the elastic of the other sleeve-holder and holds it at E² fast in the other hand. The easiest and most certain way of 45 holding the elastic is by putting the thumb behind the part E² and between those parts of the elastic cords where they form the loop. The elastics now keep the lower ends of the sleeves of their garment close to the wrists 50 of the wearer while he or she is putting on the outer garment. When the outer garment is in place, the sleeves of the first-named garment being at all times held in place are now in the proper position. The wearer now releases his handhold on the elastic cords E, and 55 the latter retract and draw themselves and the part E² up within the sleeve and out of sight.

Among the various advantages resulting from the use of my invention are, first, the 60 sleeve-holder is economical of manufacture.

It is easily put onto a sleeve and easily taken off from it. It is readily changed from one garment to another.

Another advantage of primary importance is that when applied or while on the sleeve 70 or during removal therefrom it does not wrinkle the sleeve.

What I claim as new and of my invention, and desire to secure by Letters Patent, is—

1. In a sleeve-holder, a main stiff portion, 75 catch-pins, one at each end thereof and combined therewith, an elastic connection applied to the sleeve-holder and adapted at its forward end to be held by the hand, substantially as and for the purposes specified. 80

2. In a sleeve-holder, a stiff portion provided with a cover, and a pin at each end, the adjacent end of the stiff portion embracing said ends, and an elastic connection held by said stiff portion, and adapted at its front 85 end to be grasped by the hand, substantially as and for the purposes specified.

3. In a sleeve-holder, a main stiff portion, catch-pins, one at each end thereof, and combined therewith, an elastic connection combined with the sleeve-holder, and adapted at its forward end to be held by the hand, and a loop combined with the stiff portion for holding the elastic connection in place, substantially as and for the purposes specified. 95

4. In a sleeve-holder, a stiff portion provided with a cover, and a pin at each end, the adjacent end of the stiff portion embracing said pins, and an elastic connection held by said stiff portion and adapted at its front end 100 to be grasped by the hand, and loops in connection with the stiff portion for holding the elastic connection in place, substantially as and for the purposes specified.

5. In a sleeve-holder, a metal stiff portion 105 carrying at each end a pin, around the shank of which the end of the metal is bent, and a looped part or parts struck up from the metal, and an elastic connection passing through the loop, and adapted at its lower end to be grasped by the hand, substantially as and for the purposes specified. 110

6. In a sleeve-holder, a stiff portion having means at its end portions for connecting it to the sleeve, and an elastic loop embracing 115 lengthwise the stiff portion and adapted at its lower end to be held by the hand, and means for preventing the elastic loop from slipping laterally, substantially as and for the purposes specified. 120

7. In a sleeve-holder, a stiff portion having means at its end portions for connecting it to the sleeve, and an elastic loop embracing lengthwise the stiff portion and adapted at its lower end to be held by the hand, and loops 125 connected to the stiff portion and embracing the elastic loop, substantially as and for the purposes specified.

8. In a sleeve-holder, a stiff portion B, pins C, one at each end of the stiff portion, and 130

whose shank is there embraced by the stiff portion, a cover D, embracing the stiff portion, loops H, H, and an elastic loop E, embracing the parts B, D, lengthwise, and passing through loops H, and extended below the end of the lower pin C, and adapted to be caught and held by the hand, the loops H, H, preventing the elastic loop from slipping laterally, substantially as and for the purposes specified.

CARRIE D. JACKSON.
